UNITED STATES PATENT OFFICE.

ALEXANDER RAY, OF PHILADELPHIA, PENNSYLVANIA, ASSIGNOR OF TWO-THIRDS TO CHARLES S. LOWRY AND SAMUEL BALL VAN DUSEN, BOTH OF SAME PLACE.

HOISTING APPARATUS.

SPECIFICATION forming part of Letters Patent No. 374,085, dated November 29, 1887.

Application filed June 4, 1887. Serial No. 240,226. (No model.)

To all whom it may concern:

Be it known that I, ALEXANDER RAY, of the city and county of Philadelphia, and State of Pennsylvania, have invented an Improvement in Hoisting Apparatus, of which the following is a specification.

My invention has reference to hoisting apparatus; and it consists in certain improvements, all of which are fully set forth in the following specification, and shown in the accompanying drawings, which form part thereof.

My invention has particular reference to a class of elevating devices especially designed for lifting coal and other substances from vessels, then conveying them to a suitable position over the wharf, and automatically discharging the same, but it is in nowise limited to this particular use.

Heretofore it has been customary to elevate the bucket containing the coal by one device, then turn the derrick or crane by another device, and finally discharge the contents of the bucket by hand-manipulation.

The object of my invention is to overcome the defect in such a construction by arranging the mechanism so as to perform its functions automatically, thereby increasing the speed of manipulation and greatly reducing the labor required to do the given amount of work.

In carrying out my invention I provide a derrick or crane pivoted on a vertical axis and having a weighted guy-rope adapted to return the derrick or crane to its normal position.

This derrick or crane supports a lifting-rope which is connected to a bail having pivoted thereto a bucket, and provided with a locking device for holding the bail and bucket rigidly together until fully raised, at which time the lock is operated by a stop secured to the upper

part of the derrick or crane and the bucket, being freed, tilts over by gravity and automatically discharges its contents. In addition to these features, I provide a suitable derrick or crane operating rope or cable, which may be operated to cause the derrick or crane to revolve on its vertical axis while the bucket is being raised, and preferably this cable is wound upon a drum so proportioned in relation to and combined with a lifting-drum that as the bucket

is being raised, the derrick or crane is automatically swung around, and when the bucket is in position to be discharged the derrick or crane will be fully swung around over the wharf or receptacle to receive the contents.

In the drawings, Figure 1 is a side elevation of a derrick or crane and apparatus embodying my invention. Fig. 2 is a plan view of same. Fig. 3 is a front elevation of the elevating-bucket and its connections removed, and Fig. 4 is a diagram illustrating the elevation of a modified arrangement of rope for operating the derrick or crane.

A is the derrick or crane, and has a vertical axis at B, whereby it is adapted to swing around horizontally. When not otherwise actuated, it is returned to its normal position over the boat, car, or place containing the material to be lifted by a guy-rope, J, which is guided over pulleys j' j" and connected to a weight, K. The upper end of the derrick is provided with a sheave, g, over which the lifting-cable G, terminating on its free end with a hook, passes. The other end of the cable is guided over pulleys g' g" and connected with an elevating-drum, H. By winding the drum H the bucket D, connected to the rope G by its bail E, may be elevated or lowered. The bucket D is pivoted to the bail E at e and is provided with a locking-pin, d'. To the bail is pivoted a lock, d, which is connected to a pivoted arm or lever, F, at the top of the bail by a link-connection, f. From this it will be observed that when the free end of the lever F is pressed down the lock is raised, liberating the bucket D, which by means of gravity revolves upon its axis e, automatically discharging its contents.

Pivoted or loosely connected upon the upper end of the derrick A is a movable stop, I, which is arranged in the path of the arm F of the rising bucket, whereby when the bucket is fully raised the arm F strikes the stop I and lifts the lock d to allow the bucket to discharge. As the upward movement of the lifting-rope is not easily arrested on an instant, the said stop I is made movable upwardly, so that after the lock has been tripped any further movement of the cable G will lift the stop I up

with it, and thereby overcome any tendency to breakage of the various parts and obviate the excessive wear which would otherwise be the result.

5 To swing the derrick around upon its vertical axis in opposition to the tendency of the weight K, I provide a crane-operating rope, L, which is connected at one end to a winding-drum, N, and, after passing over a pulley or eye, l, on the derrick, is connected at its other end to a weight, M. By winding up on the drum N the weight M will be drawn up until it reaches the sheave or eye l, and then any further movement of the drum will cause the 15 derrick to be swung around. The drums H and N are preferably secured to the same shaft, O, or positively connected together, so that when one revolves the other revolves also, and with fixed capacity for winding in their cables.

20 The operation of this device is now evident. If we commence to revolve the drums H and N, the cable G will be drawn in, lifting the bucket, while at the same time the cable L will be drawn in, but will have no effect until the 25 weight or other suitable stop, M, reaches the sheave or eye l, and then the crane is swung around simultaneously with the further elevation of the bucket, and the parts are so proportioned that the bucket is fully raised just 30 as the crane is swung around to the right position for the discharge to take place. By making the rope or cable L longer or shorter the derrick may be caused to swing around to any desired degree during the time of lifting 35 the bucket. It will be further observed that by this construction the bucket will be allowed to rise clear of surface obstructions before being caused to swing around horizontally.

It is evident that in place of using the weight 40 M on the free end of the rope L, the rope may be connected positively to the crane, as shown in Fig. 4, and then pass over a take-up weight, M' and then be connected with the drum N, in both of which cases the operation is substantially the same.

I do not limit myself to the details of construction here set out, as it is evident that they might be modified in a large number of ways without in the least departing from the 50 spirit of the invention.

In this application I do not claim the specific construction of the bucket and the means for tripping its lock, as this forms the subject-matter of another application.

55 Having now described my invention, what I claim as new, and desire to secure by Letters Patent, is—

1. The combination of a derrick or crane pivoted upon a vertical axis, a sheave at the 60 upper end of said derrick, an elevating rope or cable passing over said sheave, a tilting bucket supported thereby having a pivoted bail connecting with the said rope or cable, and a lock carried by the bucket to prevent 65 the bucket proper from tilting on the bail, a lever connecting with the lock and pivoted on

the bail, and a stationary projection in the path of the lever and at a fixed elevation, and a rope, substantially as described, to move the derrick on its vertical pivot, whereby, after 70 the bucket is raised and swung around in a new position, it may be automatically discharged.

2. The combination of a derrick or crane pivoted on a vertical axis, a sheave at its upper end, an elevating rope or cable passing over said sheave, a bucket having a pivoted bail secured to said rope or cable by its bail, a lock carried by said bail to lock said bucket rigidly thereto, a stationary stop or projection 80 secured to the upper part of the derrick by a loose connection as to upward movement, but fixed as to downward movement, to operate on said lock to free the bucket when fully raised, a rope or cable for turning the derrick on its 85 axis, and suitable drums for winding up both ropes or cables.

3. The combination of a derrick or crane pivoted on a vertical axis, a sheave at its upper end, an elevating rope or cable passing 90 over said sheave, a bucket having a pivoted bail secured to said rope or cable by its bail, a lock carried by said bail to lock said bucket rigidly thereto, a stationary stop or projection secured to the upper part of the derrick to operate on said lock to free the bucket when fully raised, a rope or cable for turning the derrick 95 on its axis, suitable drums for winding up both ropes or cables, of diameters sufficient to fully raise the bucket and swing the derrick 100 to its full movement in the same time, whereby as the bucket is fully raised it will be automatically turned to the proper position and then dumped.

4. The combination of a derrick or crane 105 pivoted on a vertical axis, a sheave at its upper end, an elevating rope or cable passing over said sheave, a bucket having a pivoted bail secured to said rope or cable by its bail, a lock carried by said bail to lock said bucket 110 rigidly thereto, a stationary stop or projection secured to the upper part of the derrick to operate on said lock to free the bucket when fully raised, a second sheave on the derrick, a rope or cable to swing the derrick passing over said 115 sheave, and provided with a stop to prevent its passing entirely over the sheave, a drum to wind up the bucket-rope, a drum to wind up the derrick-moving rope, and a shaft common to both of said drums, whereby the bucket is 120 raised in the same time that the derrick is swung around and with the same number of revolutions of the shaft, and the contents of 125 said bucket are automatically discharged.

5. The combination of a derrick or crane 125 pivoted on a vertical axis, a sheave at its upper end, an elevating rope or cable passing over said sheave, a bucket having a pivoted bail secured to said rope or cable by its bail, a lock carried by said bail to lock said bucket 130 rigidly thereto, a stop or projection secured to the upper part of the derrick to operate on

- said lock to free the bucket when fully raised, a second sheave on the derrick, a rope or cable to swing the derrick passing over said sheave, and provided with a stop to prevent its passing entirely over the sheave, a drum to wind up the bucket-rope, a drum to wind up the derrick-moving rope, a shaft common to both of said drums, whereby the bucket is raised in the same time that the derrick is swung around 5 and with the same number of revolutions of the shaft, and a gravity device, substantially as set out, to automatically return the derrick to its original position upon lowering the bucket.
- 15 6. The combination of the derrick or crane A, pivoted at B, the stop I, hinged to the derrick or crane near its top, the lifting-rope G, running close to the stop, the bucket D, carried by said rope and having a pivoted lock 20 provided with an extension adapted to strike the stop to trip the lock, the derrick-operating rope L, and the drums H and N for said ropes G and L, substantially as and for the purpose specified.
7. The combination of the derrick or crane 25 A, pivoted at B, the lifting-rope G, the derrick-rope L, drums H N for said ropes, a shaft common to said drums, the sheave or eye l on the derrick, and a weight and stop, M, on the free end of the rope L beyond the sheave or eye. 30
8. The combination of the derrick or crane A, pivoted at B, the lifting-rope G, the derrick-operating rope L, drums H N for said ropes, a shaft common to said drums, the sheaves or eye l on the derrick, a weight and 35 stop, M, on the free end of the rope L beyond the sheave or eye, the rope J, its guide pulleys, and weight K, to return the derrick to its normal position.

In testimony of which invention I hereunto 40 set my hand.

ALEXANDER RAY.
